US0D1017948S

(12) **United States Design Patent** (10) **Patent No.:** **US D1,017,948 S**
(45) **Date of Patent:** **** Mar. 12, 2024**

(54) **SAFE BOX**

(71) **Applicant:** **YUNDING NETWORK TECHNOLOGY (BEIJING) CO., LTD.**, Beijing (CN)

(72) **Inventor:** **Fuyao Sun**, Beijing (CN)

(73) **Assignee:** **YUNDING NETWORK TECHNOLOGY (BEIJING) CO., LTD.**, Beijing (CN)

(**) **Term:** **15 Years**

(21) **Appl. No.:** **29/790,478**

(22) **Filed:** **Nov. 30, 2021**

(30) **Foreign Application Priority Data**

Jun. 1, 2021 (CN) 202130331301.3

(51) **LOC (14) Cl.** **99-00**

(74) **Attorney, Agent, or Firm:** METIS IP LLC

(57) **CLAIM**

The ornamental design for a safe box, as shown and described.

DESCRIPTION

FIG. 1 is a front view of a safe box showing my new design, in a closed position;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof, shown in an open position; and,

FIG. 9 is a front view of FIG. 8.

The broken lines indicate portions of the safe box that form no part of the claimed design.

1 Claim, 9 Drawing Sheets
